UNITED STATES PATENT OFFICE

172,717

MEMO PAD CASING

John E. Kemper, Pomona, Calif.

Application November 2, 1953, Serial No. 27,411

Term of patent 14 years

(Cl. D74—1)

To all whom it may concern:

Be it known that I, John E. Kemper, a citizen of the United States, residing at Pomona, in the county of Los Angeles and State of California, have invented a new, original, and ornamental Design for a Memo Pad Casing, of which the following is a specification, reference being had to the accompanying drawing, forming part thereof.

In the drawing:

Fig. 1 is a top plan view of the memo pad casing, showing my new design;

Fig. 2 is a side elevational view, and

Fig. 3 is an end elevational view from either end of the memo pad casing.

I claim:

The ornamental design for a memo pad casing, substantially as shown.
